[57] CLAIM

The ornamental design for a tomb and Christian cross, as shown and described.

DESCRIPTION

FIG. 1 is a front perspective view a tomb and Christian cross showing my new design;

FIG. 2 is a left side elevational view thereof;

FIG. 3 is a right side elevational view thereof;

FIG. 4 is a front elevational view thereof; and,

FIG. 5 is a rear elevational view thereof.

The broken line showing of the date in FIGS. 1 and 4 is for illustrative purposes only and forms no part of the claimed design.
